UNITED STATES PATENT OFFICE.

HERBERT BRUSIUS, OF WHITTIER, CALIFORNIA.

ADJUSTABLE CHAIR-BACK.

1,264,265.

Specification of Letters Patent. Patented Apr. 30, 1918.

Application filed August 10, 1917. Serial No. 185,574.

To all whom it may concern:

Be it known that I, HERBERT BRUSIUS, a citizen of the United States, residing at Whittier, in the county of Los Angeles and State 5 of California, have invented new and useful Improvements in Adjustable Chair-Backs, of which the following is a specification.

This invention relates to chairs and particularly to the backs thereof and aims to 10 provide a back which may be adjusted to suit the curvature of the back of the user, in order to render it more hygienic and comfortable.

An object of the present invention is to 15 provide a novel form of back which includes a slidably mounted flexible member or frame capable of vertical and horizontal adjustment, the last mentioned adjustment permitting of various degrees of curvature, which, 20 together with the vertical adjustment will enable the back to be regulated to suit persons of various heights and builds.

A further object is to provide a novel 25 means, whereby, when the back is adjusted it may be secured in such adjusted position, the securing means permitting of the adjustment being changed and at any time restored, so that when the desired adjustment is obtained it may be again readily found.

30 With these and other objects in view the invention consists in the following novel combination and arrangement of parts, hereinafter more fully described and illustrated in the accompanying drawings, in which—

Figure 1 is a front elevation of a chair provided with a back constructed in accordance with the present invention;

Fig. 2 is a side elevation of the same;

40 Fig. 3 is an enlarged central vertical section taken through a chair back and illustrating the means for obtaining the various adjustments of the flexible member of frame;

45 Fig. 4 is a detailed perspective view of a portion of the lower end of the back, illustrating the sliding connection of the flexible frame with the back and a means of holding the frame in its flexed position;

50 Fig. 5 is a detailed vertical sectional view on the line 5—5 of Fig. 2;

Fig. 6 is a cross-sectional view on the line 6—6 of Fig. 2;

55 Fig. 7 is a detailed vertical sectional view on the line 7—7 of Fig. 1;

Fig. 8 is a detail view of a section of the

adjusting rod, the parts being shown separated.

Similar characters of reference denote corresponding parts throughout the several 60 views of the drawings.

In the drawings, there is shown a chair which includes a seat 10 and a back 11 of any preferred construction, it being only necessary that the back be of skeleton 65 formation in order to provide a supporting frame 12.

The supporting frame includes vertical side bars 13 and upper and lower connecting bars 14 and 15 respectively. 70

The invention resides particularly in the novel form of flexible adjusting member which is mounted within the supporting frame 12. This member comprises a frame which includes the upper and lower transverse bars 16 and 17 respectively, both of which are pivotally secured to the side bars 13 by screws or bolts 18. The screws 18 are received within slots 19 provided in the side bars 13, by means of which the bars 16 and 17 are moved longitudinally of the frame 12. Interposed between the ends of the bars 16 and 17 and the side bars 13 are springs 20, which are provided with openings 21 which are adapted to receive the 85 screws 18, the said springs providing a frictional engagement between the said bars 16 and 17 and the supporting frame. The inner faces of the side bars 13 are grooved as indicated at 22, the width of this groove 90 being co-extensive with the width of the springs 21 so as to retain them in proper position.

The bars 16 and 17 are provided with a flexible connection, in the form of flexible 95 bars or rods 23, one end of which is secured to the bar 16, while the other end is loosely received within sockets 24, of the bars 17, so that there is provided a slidably connection between these flexible rods and the said 100 bar.

Secured to the upper and lower bars 14 and 15 of the supporting frame is a longitudinal bar 25, which is provided with a longitudinal metal lined slot 26, within 105 which is slidably mounted a nut 27. Mounted within this nut is a threaded rod 28, which has one end received within a socket or thimble 29 secured to a freely mounted transverse bar 30. The opposite 110 end of this rod 28 is provided with an adjusting handle 31. The threaded rod 28 is

preferably formed in sections, the inner section which is connected to the transverse bar 30 being detachably secured to the outer section which carries the adjusting handle 31, by means of a reduced threaded extension carried by the said outer section, which is engageable in a threaded socket formed in the inner section. This enables the outer section together with the adjusting handle 31 to be removed if desired, after the back has been adjusted, so that the said handle 31 will not project beyond the plane of the back to interfere or catch in the clothing of persons passing closely thereto.

15 The bar 30 is slidably secured to each of the flexible rods 23 by means of eyes 32, so that when the threaded rod 22 is engaged with the socket or thimble 29 and moved along the slot 26 it will carry with it the bar 30, so as to position the said bar at any point intermediate the ends of the rods 23.

By adjusting the rod 28 toward the flexible rods 23, they may be flexed so as to provide various degrees of curvature, and by 25 moving the said threaded rods along the slot 26 various forms of curvature may be obtained.

The lower or free ends of the rods 23 are provided with transverse apertures 33, which 30 are adapted to receive angular engaging pins 34, which are guided in eyes 35 secured to the bar 17. The pins 34 are carried by a rod 36, which is slidably mounted in eyes 37, which are also secured to the bar 17. Thus 35 it will be seen that after the desired lateral or curved adjustment is made, the rods 23 may be secured in their adjusted position by means of the pins 34. After the desired adjustment is obtained to suit a particular 40 user of the chair, the chair may be adjusted to suit other persons and again restored to its original adjustment by inserting the pins 33 in the proper openings, so that it will not be necessary to experiment each time an 45 adjustment is made.

By the construction above described various degrees of curvature may be obtained and the form of curvature varied to suit.

It is thought that from the foregoing description taken in connection with the accompanying drawings, the operation and advantages of the invention will be apparent and that a more extended description is unnecessary. The right is reserved to make 55 such changes as will properly fall within the scope of the appended claims.

Having described the invention, what is claimed is:

1. An adjustable back for chairs comprising a supporting frame, a supplemental frame mounted therein and adapted to normally lie within the transverse plane of the main frame, means for adjusting said supplemental frame longitudinally of the supporting frame and means for adjusting the

supplemental frame to project the same out of alignment with the supporting frame.

2. An adjustable back for chairs comprising a supporting frame, a supplemental frame mounted therein and adapted to normally lie within the transverse plane of the main frame, means for adjusting said supplemental frame longitudinally of the supporting frame, means for adjusting the supplemental frame to project the same out of alignment with the supporting frame and auxiliary means for holding the supplemental frame in its adjusted position.

3. An adjustable back for chairs comprising a supporting frame, a supplemental frame mounted therein, said supplemental frame comprising cross-bars slidably engaging the supporting frame and a flexible connection between said bars, means for adjusting said frame longitudinally of the supporting frame and means for adjusting the supplemental frame to project the same out of alignment with the supporting frame.

4. An adjustable back for chairs comprising a supporting frame, a supplemental frame mounted therein, said supplemental frame comprising cross-bars slidably and pivotally engaging the supporting frame and a flexible connection between said bars, means for adjusting the supplemental frame longitudinally of the supporting frame and means for adjusting the supplemental frame to project the same out of alignment with the supporting frame.

5. An adjustable back for chairs comprising a supporting frame, a flexible supplemental frame slidably mounted therein and adapted to normally lie within the transverse plane of the main frame, and means for adjusting said supplemental frame to project the same out of alignment with the supporting frame.

6. An adjustable back for chairs comprising a supporting frame, cross-bars slidably and pivotally mounted therein, flexible rods secured to one of said cross-bars and freely engaging the other cross-bar, means for adjusting said cross-bars longitudinally of the supporting frame and means for adjusting the flexible rods to project them out of alignment with said supporting frame.

7. An adjustable back for chairs comprising a supporting frame, cross-bars slidably and pivotally mounted therein, flexible rods secured to one of said cross-bars and freely engaging the other cross-bar, securing devices engageable with the free ends of the flexible rods, means for adjusting said frame and means for adjusting the flexible rods to project them out of alignment with the said supporting frame.

8. An adjustable back for chairs comprising a supporting frame, a flexible supplemental frame slidably mounted therein, a resilient pivotal connection between the sup-

porting frame and each end of the supplemental frame and means for adjusting the supplemental frame to project the same out of alinement with the supporting frame.

- 5 9. An adjustable back for chairs comprising a supporting frame, a flexible supplemental frame slidably mounted therein, a resilient pivotal connection between the supporting frame and each end of the supplemental frame, and an adjusting screw for projecting the supplemental frame out of alinement with the supporting frame.
- 10 10. An adjustable back for chairs comprising a supporting frame, a flexible supplemental frame slidably mounted therein, a resilient pivotal connection between the supporting frame and each end of the supplemental frame and means for adjusting the supplemental frame to project the same out of alinement with the supporting frame.

10. An adjustable back for chairs comprising a supporting frame, a flexible supplemental frame slidably mounted therein, 15 a resilient pivotal connection between the supporting frame and each end of the supplemental frame and a slidably mounted adjusting screw for projecting the supplemental frame out of alinement with the sup- 20 porting frame.

In testimony whereof I affix my signature.

HERBERT BRUSIUS.
